CONTAINER BLANK

Walter G. Reagan, Lebanon, Ind.

Application August 29, 1936, Serial No. 98,509

8 Claims. (Cl. 229—1.5)

It has long been customary, in the retail vending of popped corn, to package the same in ordinary commercial paper bags or boxes in various sizes, depending upon the charged price. The vendor has been under the necessity of carrying a stock of bags of different sizes and a package of this kind is somewhat difficult to handle during consumption of the popped corn. A reasonably grease impervious bag is relatively expensive.

10 The object of my present invention is to provide a paper blank so formed that a vendor may readily develop it into a conical container in any one of a plurality of sizes to form a container of desired capacity, which container may be more 15 readily handled by the consumer and the cost of which, to the merchant, will be materially less than the preformed bags now commonly used.

While the blank has been primarily designed as a popped corn container, it will, of course, be 20 readily understood that containers formed from the blanks will be equally useful in the vending of a large variety of articles.

The accompanying drawing illustrates my invention:

25 Fig. 1 is a face view of the blank,

Fig. 2 a perspective view of one of the blanks formed into a large capacity container,

Fig. 3 a similar view of the same blank formed into a smaller capacity container, and

30 Fig. 4 a perspective view showing the blank in the preliminary stage of development into a container.

In the drawing, 10 indicates the main body of the blank, a portion of the edge of which, as indicated at 11, is arcuate, struck approximately from a center 12 in or near the opposite edge portion 13 which is straight, or nearly straight. The arcuate portion 11 at one end is flanked by an edge portion 14 and at the other end by an edge portion 15 which, in turn, is flanked by an edge portion 16 which is substantially parallel with edge portion 14 and connects with one end of edge portion 13. At the corner formed by edges 13 and 14 is a locking tongue 17 which, at its junction with edge portion 13, forms an entrant notch 18.

45 Formed through the main body 10 adjacent the arcuate edge 11 and variably spaced from edge 14 are slits A and B.

The above described blank is conveniently 50 formed of comparatively thin, but reasonably stiff and tough paper, although, of course, it can be formed from any other suitable sheet material.

The user, by grasping edge 16 and swinging the 55 same upwardly and inwardly about an axis substantially parallel with said edge to roll the blank

into a loose roll, as shown in Fig. 4, may readily insert tongue 17 into slit A, whereupon, by placing the two hands at opposite ends of the rolled blank, as shown in Fig. 4, and simultaneously exerting axial pressure and oppositely rotating 5 the hands in the direction indicated by the arrow, the blank may be tightened to true conical form as a container, as illustrated in Fig. 3. If the tongue 17 be inserted in the slit B, a large size container will be produced, as indicated in 10 Fig. 2. The blank is dubbed off at 15 in order that the adjacent portion of the blank, when brought to container form, will, by reason of its resiliency, snuggle against the inner surface of 15 the cone. This dubbing off is not absolutely essential but it contributes materially to the production of a better looking container for when the blank is so formed, the edge portions 15 and 16 hug the inner surface of the cone without forming a loose flap.

20 It will be readily understood that by the simple expedient of providing a multiplicity of slits like the slits A and B variably spaced, the available range of container sizes may be increased. The arcuate edge 11 develops into an even ended cone, 25 which, of course, is desirable for looks though not absolutely essential.

It is desirable also that the edge 13' be straight from edge 16 to approximately slightly beyond center point 12 and the remaining portion continue to its junction with the notch 18 at a very slight angle, as indicated in Fig. 1, as otherwise 30 there is a slight tendency to looseness of the edge portion 13 along the outer face of the cone.

When the blank is conified, the apex of the cone 35 will be adjacent edge 13—13' and in the claims this line is considered a base line, a medial perpendicular to which will divide the blank into two halves, one of which halves will carry the tongue and slits.

40 As stated above the apex of the cone formed from the blank will be adjacent the edge 13, 13', one corner of which carries the tongue 17. The slit for receiving this tongue must be in the upper half of the blank, considering the apex line as 45 the base line.

I claim as my invention:

1. A blank for conical packages, comprising a polygonal sheet of flexible somewhat resilient material, such as paper, provided at one corner 50 with a locking tongue flanking a re-entrant notch and also having a tongue-receiving slit within that half of the blank which carries the tongue and within the quadrant of said half most remote from said tongue.

2. A blank for conical packages, comprising a polygonal sheet of flexible somewhat resilient material, such as paper, provided at one corner with a locking tongue flanking a re-entrant notch and also having a plurality of spaced tongue-receiving slits within that half of the blank which carries the tongue and within the quadrant of said half most remote from said tongue.
3. A blank of the character specified in claim 1 wherein the edge portion of the blank opposite the tongue is outwardly arcuate.
4. A blank of the character specified in claim 2 wherein the edge portion of the blank opposite the tongue is outwardly arcuate.
5. A blank for conical packages, comprising a polygonal sheet of flexible somewhat resilient material, such as paper, provided at one corner of the base edge with a locking tongue flanking a re-entrant notch, and also having a tongue-receiving slit within that portion of the blank which lies above the medial line of the blank substantially parallel the base line.
6. A blank for conical packages, comprising a polygonal sheet of flexible somewhat resilient material, such as paper, provided at one corner of the base edge with a locking tongue flanking a reentrant notch, and also having two spaced tongue-receiving slits within that half of the blank which lies above the medial line substantially paralleling the base line.
7. A blank of the character specified in claim 5 wherein the edge portion of the blank opposite the tongue is outwardly arcuate.
8. A blank of the character specified in claim 6 wherein the edge of the blank opposite the tongue is outwardly arcuate.

WALTER G. REAGAN.
